UNITED STATES PATENT OFFICE.

FREDERICK MANKEY, OF WILLIAMSPORT, PENNSYLVANIA.

DESIGN FOR A PANEL.

SPECIFICATION forming part of Design No. 16,238, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photographs, forming part hereof.

Figure 1 represents a panel having my new design. Figs. 2 and 3 show combinations of panels similar to Fig. 1.

Similar letters of reference indicate like parts.

My new design consists, as shown in Fig. 1, of a central rectangular elevation, A, of frusto-pyramidal form, having curved or rounded sides and surmounted by a square elevation, A'. There are also four elevations, B C D E, arranged diagonally upon the panel, and each having one side parallel to a side of elevation A. These elevations are similar in conformation to the elevation A, but are of elongated shape. Two of said elevations, B and C, are incomplete, as shown. Between the elevations B C D E are elevations F G H I. Between the aforesaid elevations are spaces or channels J K, extending diagonally across the panel.

Upon the elevations G H I are ornamental figures—such as L, for example. In the center of the panel shown in Fig. 2 are formed three small elevations similar to A, and above and below the central elevation are chevrons.

In Fig. 3 a panel is shown at the center of which are two rectangular elevations, G H H G, two rectangular elevations F F F F, and between said elevations are chevrons.

I claim as my invention—

1. The design for a panel, substantially as herein set forth, and as shown in Fig. 1, consisting in a central frusto-pyramidal rectangular elevation, A, having rounded sides and surmounted by the flat-surfaced elevation A', the diagonally-disposed elevations B C D E, the intermediate elevations, F G H I, and the spaces or channels J K.

2. The design for a panel, substantially as herein set forth, and as shown in Fig. 2.

3. The design for a panel, substantially as herein set forth, and as shown in Fig. 3.

FREDERICK MANKEY.
